(57) **CLAIM**

The ornamental design for a spa control panel, as shown and described.

DESCRIPTION

FIG. 1 is a top plan view of a spa control panel showing my new design;

FIG. 2 is a bottom view thereof;

FIG. 3 is a side view of one side thereof;

FIG. 4 is a side view of the opposite side thereof;

FIG. 5 is a first end view thereof;

FIG. 6 is a view of the opposite end thereof; and,

FIG. 7 is a top perspective view thereof.

The broken lines shown in the drawings represent unclaimed structure of the spa control panel and form no part thereof.
